FIG. 1.

FIG. 2.

INVENTOR

D. W. Norwood

BY *Robert H. Young*

ATTORNEY

UNITED STATES PATENT OFFICE.

DONALD W. NORWOOD, OF HONOLULU, TERRITORY OF HAWAII.

TELEPHONE RECEIVER.

Application filed September 24, 1925. Serial No. 58,342.

This invention relates to electrical receivers such as are used in electrical communication, and the primary object is the provision of a receiver which will be exceedingly thin and yet have improved tone characteristics and efficiency in reproduction of speech.

My invention utilizes a helical permanent magnet which adjoins the rim of a magnetic diaphragm, a single electrical coil of large diameter being placed within the permanent magnet to cooperate with a soft iron core within the coil. The various parts of the receiver are all arranged concentrically and since all are of large diameter compared with their depth, an exceedingly thin receiver is obtained which will nevertheless be extremely efficient since the energized coil of wire is entirely surrounded by the magnetic flux path. The center of the diaphragm is closely adjacent to the center of the soft iron core, the remaining points of the diaphragm being spaced from the adjacent portions of the core varying distances, depending upon the distance from the center so that the magnetic flux acting on any point in the diaphragm is proportional to the displacement desired at that point. The diaphragm will thus be caused to vibrate throughout its whole surface in a symmetrical manner and without distorting the signals transmitted. Means is provided so that the spacing for air gap existing between the diaphragm and the soft iron core may be varied so as to increase or decrease the loudness of the tone and the speed characteristics.

More detailed objects and advantages of my invention will be more fully set forth in the attached specification, in the claims and in the drawings in which

Fig. 1 is a vertical central section through the receiver, and

Fig. 2 is a perspective view of the helical magnet utilized.

Referring more particularly to the drawings, a lower casing 1 is provided to contain the various parts of the receiver, this casing being formed of a lower portion 2 and an end plate 3 threaded thereon by means of the threads 4 in the customary manner. This casing may be made of hard rubber or other insulating material. The end plate 3 is provided with a central aperture 5 through which sound is transmitted. The

end plate 3 is provided with a flange 6 which bears against the rim of a circular magnetic diaphragm 7, a suitable air space being provided between the diaphragm and the central portions of the end plate.

Closely adjacent to the diaphragm is provided a soft iron core 8 in the form of a disk with a laterally projecting end flange 9. The end of this flange is in contact with the lower end of a permanent helical magnet 10 herein shown as consisting of a few turns of steel. This magnet is provided at one end thereof with an upper face 11 which is in contact with the outer edge of the diaphragm throughout nearly the complete circular extent of the latter. At its other end the permanent magnet, as before stated, is in contact with the soft iron core 8, and the diaphragm 7 is thus energized by the permanent magnet and the diaphragm held slightly concaved inwardly by uniformly distributed series of flux lines which have their greatest intensity at the center of the diaphragm. The spacing between the core and the diaphragm is so designed with its minimum extent at the center that the magnetic flux acting on any point in the diaphragm is proportional to the displacement desired at that point.

Placed within the permanent magnet and immediately outside of the body portion of the soft iron core, so as to rest upon the lower flange 9 thereof, is a single large diameter coil of wire indicated at 12, the two ends of which are connected to the two binding posts 13 and 14 where they are adapted to be connected to an external energizing circuit. The coil will therefore be entirely surrounded by the flux path of the receiver and since it is immediately outside of and adjacent to the soft iron core, the variations of magnetic flux in this core, due to changes in the current flowing through the coil, will be produced in an efficient and accurate manner.

The helical permanent magnet is preferably of large diameter as compared with its longitudinal extent as shown in Fig. 1, this longitudinal extent being preferably slightly larger than the final position it obtains when in place within the casing, so that a spring tension will be exerted by it to maintain the parts in place within the casing. The air gap between the diaphragm and the soft iron core may be varied therefore by

screwing the end plate of the casing on or off as desired, such as resulting in the compression or releasing of the helical magnet. The space between the various turns of the magnet may be either left vacant or be filled with a helical strip of suitable yielding material of a non-magnetic character, such as sponge rubber as indicated at 15.

The diameter of the various parts, it will be noted, is large compared with their vertical extent and the various essential elements of the receiver are all mounted concentrically so that a receiver of very flat appearance is provided, thus taking up little space at the side of the wearer's head. The various flux paths through the various portions of the air gap are all symmetrical for the same distance in spacing from the axis of symmetry, due to the symmetrical arrangement of the parts. The distribution of the magnetic flux lines generated from the permanent magnet is practically uniform or symmetrical, since this magnet is in close contact along practically its entire surface with the rim of the diaphragm, and in close contact at its lower portion with the entire circular extent of a flange of the soft iron core. If desired the helical magnet may be replaced by a series of closely positioned vertically extending balance magnets arranged with their longitudinal axis parallel to the axis of symmetry of the casing.

I am aware that various other changes may be made without departing from the scope of my invention, the preferred form of which has been shown herein, by way of example, and I do not desire to have my invention restricted to the exact form shown and described herein.

40 I claim:

1. In an electrical receiver, an electro-magnet, a diaphragm therefor, and a helical permanent magnet cooperating with said diaphragm and in contact therewith for a substantial distance on the edge of said diaphragm.

2. In an electrical receiver, in combination, an electro-magnet, a diaphragm therefor, and a compressible helical permanent magnet having a diameter many times the

axial length thereof, cooperating with the diaphragm.

3. In a device of the class described, in combination, a coil of wire, a soft iron core therefor, and a diaphragm cooperating with said core, the flux path through all points concentric with the center of the diaphragm being the same and the intensity of the flux progressively decreasing as the distance from the center of the diaphragm increases. 60

4. In a device of the class described, in combination, a casing, a coil of wire, a soft iron core therefor, a circular diaphragm having its center closely adjacent the center of said core, a permanent magnet interconnecting said diaphragm at substantially all of its outside portions with the said core through paths of substantially uniform flux resistance, the said core magnet and diaphragm and the air space between the diaphragm and the core constituting a flux path which gradually decreases in resistance towards the center of the diaphragm. 70

5. In an electrical receiver, in combination, a coil of wire, a soft iron core therefor of large diameter as compared with depth, a large diameter annular permanent magnet, and a diaphragm having a portion closely adjacent to said core, and a portion adjoining said permanent magnet, and so means for varying the space between the diaphragm and the core. 75

6. In a receiver, an electro-magnet, a single helical permanent magnet, a diaphragm cooperating with said magnets and arranged adjacent thereto, so that the entire diaphragm is utilized uniformly for a magnetic flux path, with the flux lines all directed radially and of substantially equal intensity at points limited the same distance from the center of said diaphragm. 85

7. In a receiver, a diaphragm, a coil of wire, and a magnetic flux path cooperating with said coil of wire in said diaphragm and spaced from said diaphragm to provide an air gap, the magnetic flux acting on any point in the diaphragm being proportional to the displacement desired at that point. 95

In testimony whereof I affix my signature.
DONALD W. NORWOOD.
